UNITED STATES PATENT OFFICE.

HENRIK HILLBOM, OF WALLINGFORD, CONNECTICUT, ASSIGNOR TO R. WALLACE & SONS MFG. CO., OF WALLINGFORD, CONNECTICUT, A CORPORATION.

DESIGN FOR A SPOON, FORK, OR SIMILAR ARTICLE.

46,281.

Specification for Design.

Patented Aug. 18, 1914.

Application filed June 3, 1914. Serial No. 842,784. Term of patent 7 years.

To all whom it may concern:

Be it known that I, HENRIK HILLBOM, a citizen of the United States, residing at Wallingford, in the county of New Haven and State of Connecticut, have invented a new, original, and ornamental Design for a Spoon, Fork, or Similar Article, of which the following is a specification, reference being had to the accompanying drawing, forming part thereof.

Figure 1 is a face view of a spoon, fork or similar article showing my new design. Fig. 2 is a detail perspective view.

I claim:—

The ornamental design for a spoon, fork or similar article, as shown.

HENRIK HILLBOM.
